UNITED STATES PATENT OFFICE.

HENRI J. J. CHARLIER, OF PHILADELPHIA, PENNSYLVANIA.

FURNACE.

SPECIFICATION forming part of Letters Patent No. 649,567, dated May 15, 1900.

Application filed February 19, 1900. Serial No. 5,697. (No model.)

To all whom it may concern:

Be it known that I, HENRI J. J. CHARLIER, a citizen of the Republic of France, residing in the city and county of Philadelphia, in the 5 State of Pennsylvania, have invented a certain new and useful Improvement in Furnaces, of which the following is a true and exact description, reference being had to the accompanying drawing, which forms a part 10 thereof.

My invention relates to the construction and manipulation of furnaces especially intended and adapted for melting metals, the 15 object of my invention being to provide a furnace of great simplicity of construction, one which can be rotated so as to bring different parts of its walls under the influence of the heating-gases and which may be readily moved in other ways and other directions.

20 To these ends my invention consists, generally speaking, in constructing my furnace of cylindrical shape and with openings in its ends for the entrance of heating-gases and exit of products of combustion and in supporting and providing for the rotation of the 25 furnace by suspending it on flexible loops passing over its ends by overhead pulleys or similar devices. Preferably the upper ends of the flexible loops are supported on opposite 30 ends of a central pivotally-supported beam, whereby the furnace can be made to tilt in either direction, and preferably, also, I support the pulleys for the flexible loops from an overhead crane, so as to provide for the 35 shifting of the furnace in horizontal or other directions in accordance with the usual capacities of cranes.

Reference being now had to the drawing in which my invention is illustrated, A is the 40 cylindrical furnace, lined with fire-brick, as shown at A', and having at the ends openings A² and A³ for the entrance of fuel-gas and the exit of products of combustion.

A⁴ indicates a tap-hole through which the 45 melted metal can be drawn off into a receptacle H or other convenient receptacle.

B B indicate chain-wheels surrounding the ends of the cylinder.

C C are flexible loops, preferably chains, as 50 shown, which pass around the chain-wheels B and also around pulleys, as indicated at

C' C', said pulleys being journaled in supports C², which, as shown, are supported in turn on the notched ends D² D² of the beam D, centrally and pivotally supported at D' on 55 a chain E, the upper end of which is secured to a trolley E' by an adjusting-nut e', said trolley running on a track E², supported on the arm E³ of a crane E³ E⁴.

F indicates a device whereby combustible 60 material, gaseous or otherwise, can be thrown into the end A² of the cylindrical furnace. As shown, it consists of a cylinder F', having a movable bottom F², supported on an adjusting-screw F³, and a perforated top F⁴, 65 above which is the chamber F⁵, having an air-blast pipe F⁶ leading into one end of an exit-nozzle F⁷, lying opposite to the blast-pipe. In practice the cylinder F is charged with 70 coal-dust, which is forced up through the perforated bottom F⁴ by means of the movable bottom F², the coal-dust being caught up by the air entering through the blast-pipe F⁶ and blown through the nozzle F⁷ into the furnace.

G is a stack, and, as shown, a recess g is 75 formed in the stack, in which is placed the horizontally-movable chamber G', having a lateral port G⁸, which can be made to register with the stack, and an end port or opening G⁹, which can be made to register with exit-opening A³ of the furnace. This device G' is supported by wheels G⁴ on a track, (indicated at G⁵.)

In practice the furnace A is gradually heated up—as, for instance, by first burning 85 wood in it and then forcing a gradually-increasing amount of mixed air and coal-dust into it until it is at a white heat. It is then charged with metal, most conveniently through its open end A³, and this end is then 90 brought into registry with the movable flue device G' and further fuel blown in to keep the furnace at the necessary heat. From time to time during the heating of the metal the furnace is partially revolved by means 95 of the flexible chain C, so as to bring heated portions of the walls beneath the metal and subject the portions of the wall which have served as the hearth to the heating action of the flames. When the metal is melted, it is 100 tapped off through the tap-hole A⁴; but prior thereto it can be, if desired, moved to any

position within the range of the crane. It will be obvious that, if desired, the furnace can be discharged through either of its ends A² or A³ by tilting the beam D and that the 5 furnace is capable of assuming almost any desired position, owing to the character of its described connections.

Having now described my invention, what I claim as new, and desire to secure by Letters 10 Patent, is—

1. A cylindrical furnace, as A, having openings, as A² A³, at its ends for the entrance of fuel and exit of products of combustion in combination with rotatable flexible loops, as 15 C C, supported on overhead pulleys and passing around and supporting the ends of the furnace and means for supporting and shifting in a horizontal plane said supporting-pulleys and the furnace supported thereon.

2. A cylindrical furnace, as A, having openings, as A² A³, at its ends for the entrance of fuel and exit of products of combustion in combination with a pivotally-supported beam, as D, pulleys C' C' supported on the ends of 25 said beam and rotatable flexible loops sup-

ported on said pulleys and passing under and supporting the ends of the furnace.

3. A cylindrical furnace, as A, having openings A² and A³ in its ends for the entrance of fuel and exit of products of combustion in 30 combination with a crane and means including flexible loops C C whereby the furnace is suspended from the crane and rotated by means of said flexible loops passing around the ends of the furnace.

4. A cylindrical furnace, as A, having openings A² and A³ in its ends for the entrance of fuel and exit of products of combustion in combination with a crane, a beam D pivotally suspended at its center from said crane, pulleys as C' C' supported on the ends of said beam and flexible loops C C, passing around said pulleys and around the ends of the furnace said chains supporting the furnace and serving to rotate it at will. 35 40

HENRI J. J. CHARLIER.
